SEWING MACHINE

Dewey L. Conner, Grand Rapids, Mich.

Application June 8, 1933, Serial No. 674,791

5 Claims. (Cl. 112—158)

The present invention relates to sewing machines; and its object is, generally, to provide an improved device for sewing fasteners, such as buttons and the like, on garments, or other bases; and more particularly, to provide improved mechanism for oscillating the needle of such a machine sidewise so as to pass alternately through spaced holes in the fastener; and further, to provide said mechanism mounted on sewing machine parts of usual type; and further, to provide said mechanism adapted to form embroidery stitching and button hole stitching on such a fabric or base.

These and any other and more specific objects hereinafter appearing are attained by, and the invention finds preferable embodiment in, the device, including said mechanism, particularly described in the body of this specification and illustrated by the accompanying drawings, in which:

Figure 1 is a view in perspective of portions of a sewing machine with my device applied thereto;

Figure 2 is a horizontal sectional view of portions of said device and said machine taken on line 2—2 of Figure 3;

Figure 3 is an elevational front view of said device and portions of said machine partially sectioned on line 3—3 of Figure 2;

Figure 4 is an elevational right hand side (or inner side) view of said device and machine portions, partially sectioned on line 4—4 of Figures 2 and 3;

Figures 5, 6 and 7 are elevational right hand side (or inner side) views of portions of the mechanism for oscillating the machine's needle, shown in different positions and one of the parts being sectioned on a vertical plane corresponding to line 5—5 of Figure 3;

Figures 8 and 9 are bottom plan views of portions of said mechanism for oscillating the machine's needle, showing the parts in different positions;

Figure 10 is an elevational left hand side (or outer side) view of portions of said mechanism;

Figures 11, 12 and 13 are top plan views of portions of said mechanism showing the parts in different positions, certain parts being sectioned on line 11—11 of Figure 3;

Figure 14 is a top plan view of needle-mounting means;

Figure 15 is an elevational view thereof and a sectional view of adjacent parts taken on line 15—15 of Figure 9;

Figure 16 is a view of a fabric showing embroidery stitching; and

Figure 17 is a view of a fabric showing button-hole stitching.

In the embodiment of the invention illustrated by these drawings, my device is shown detachably applied to a sewing machine of ordinary type having the table or work support 1 and the horizontal arm 2 extending thereover in whose head 3 the vertically movable bar 4 carrying the usual detachable presser foot is slidable and the needle-carrying bar 5 reciprocates in the sewing operation, usual thread-tensioning means 6 and 7 being indicated in Figure 1.

My device comprises suitable means for positioning—i. e., moving and holding in moved position—the fasteners in proper location on the fabric or base 9 to which they are to be sewed, and comprises also mechanism for oscillating sidewise the needle 10 of the sewing machine so as to pass alternately through a pair of spaced holes in said fasteners.

The means for thus positioning such fasteners, as the flat buttons 8, 8¹, is particularly well shown in Figure 2 and is detachably mounted on said bar 4 (after removing therefrom the usual presser foot), the device including a plate having a horizontal portion or flange 13 with a notch 14 receiving the flattened portion 15 of bar 4, this flange being clamped between said bar's shoulder 16 and the knurled nut 17 threaded on this bar. On this flange 13 is pivoted at 18 a lever arm 19 having an operating handle portion 20 and a recess with angularly disposed sides 21 adapted to receive and hold the button 8 or 8¹, the button being yieldingly pressed into such holding engagement with the sides 21 by a spring 22. This spring has an inwardly extending flange or edge portion 23 engaging the under side of the button, while said sides 21 have grooves 24 receiving the opposite edge of the button to hold the same in place in the lever arm 19, this arm (when lowered by the usual means for lowering and raising the presser foot bar of such machines) serving as a presser foot to hold the button in proper relation to the fabric 9 on the plate 25 of the machine's table, below which plate the shuttle (not shown) operates. The degree to which this lever arm 19 may be turned on pivot 18 is limited by adjustable stops, the screws 26 threaded in the arm, which stops are engaged by the rearward extension 27 of the flange 13.

In sewing buttons 8 having one pair of holes 11², 11³, as shown in Figure 1, the arm 19 of said positioning means is turned to a position where-

in the button is held with its holes aligned in the direction of the needle's oscillation (herein-after explained) and the arm is fastened in said position by the screws 26, and in the sewing operation the needle passes through these holes alternately; but in sewing buttons 8¹ having two pairs of holes 11, 11¹ and 12, 12¹, as shown in Figures 2 and 3, the arm 19 is turned, (the screws 26 being adjusted to proper limiting position), 10 say first to the right hand (as seen in said views) so that the button 8¹ is held with its holes 11, 11¹ aligned as aforesaid, whereupon the needle in its oscillation passes through these holes alternately; this done, the arm 19 is turned toward the left hand thus aligning the other pair of its holes 12, 12¹, as aforesaid, and the needle passes through these two holes alternately.

The mechanism for thus oscillating the needle 10 includes: a member carried by the needle bar 5 and having a body 28 which, in the particular construction shown, is made up of spaced side plates 29 connected at their ends by cross bars or blocks 30 and 31, said body being detachably mounted on the needle bar by a set screw 32 passing therethrough and threaded in the block 30; a needle carrier plate 33 on the under side of said body and pivoted at 34 on the bottom of block 31 so as to turn horizontally; and a lever 35 pivoted at 36 on the underside of plate 33 so as to turn horizontally, having one of its arms 37 bent upwardly and extending through a slot 38 in the plate 33 and thence beyond the adjacent end of said plate. The lever 35 and plate 33 are yieldingly held in parallel relation 35 as seen in Figure 9 by a U-shaped spring 39 fastened in its middle at 40 on said plate and having arms 41 pressing on the opposite edges of the other arm 42 of the lever.

The needle 10 is carried by plate 33 so that the 40 turning of said plate on its pivotal mounting 34 oscillates the needle sidewise. The needle is thus carried by any suitable means on the said plate, preferably detachably as shown, as on a small mounting plate or block 43 tightly fitting in a 45 socket 44 in plate 33 and held therein by an overlying bar 45 having screws 46 extending therethrough and threaded in plate 33. The needle extends downwardly through a large opening 47 in the lever 35. The movement of plate 33 on 50 said body 28 about the pivot 34 is limited by adjustable stops, the screws 48 threaded in the spaced plates 29 and adapted to strike the post 49 of plate 33. Buttons whose pair of holes are at different distances apart are adapted to be 55 used by properly adjusting these stops. A leaf spring 50 mounted on said post presses on the upper side of block 30 sliding thereon in the relative movement of said body 28 and plate 33.

Another member 53 of the mechanism for 60 oscillating the needle is carried in a position fixed relatively to the vertical reciprocation of the needle bar 5, as on the upwardly-forwardly curved arm or flange 51 of the plate 13 which is mounted on the presser bar 4. On the right hand side (or inner side) of this arm 51 said member 65 53 is pivoted at 52 and is a triangularly shaped plate or trigger having upwardly diverging opposite sides 54, 55, along one of which the end portion 56 of lever 35 moves in the movement of 70 needle bar 5 in which the needle passes through one of the holes of any pair thereof in the button and along the other one of which sides said end portion moves in the needle's movement through the other hole of said pair.

75 The needle oscillating mechanism operates in

the following manner: Assuming now that the needle has just made a stitch through the button's forward hole 11¹, 12¹ (Figure 2) or 11² (Figure 1) and is rising, the parts are in the following positions: The plate 33 is in forward swung position, the lever 35 thereon is in its neutral or middle position seen in Figure 9, and the member 53 is in the turned position seen in Figure 6. When the needle bar 5 rises far enough, the end portion 56 of lever 35 engages the lower portion 10 of side 55 of member 53 thus turning lever 35 rearwardly, i. e. to its position seen in Figure 8 (which is a bottom plan view) and thereby swings plate 33 with it carrying the needle to rearward position preparatory to next stitching through 15 the button's rearward hole 11, 12 (Figure 2) or 11² (Figure 1).

When said end portion 56 in this upward movement of the needle bar 5 passes above the pivot 52 of member 53, this end portion turns 20 said member 53 toward the position seen in Figure 5 whereupon this member's pin 57 (extending through slot 58 in flange 51) tilts the spring 59 (pivoted at 60 on said flange) from the position seen in Figure 10 and said spring suddenly urges 25 said member to its opposite position seen in Figure 5.

The needle bar now moving downwardly and carrying said end portion 56 of lever 35 along the side 55 of member 53 stitches through the 30 button's rearward hole 11, 12 (Figure 2) or 11² (Figure 1); and when said end portion 56 passes below the point 61 of said member the spring 41 is permitted to return lever 35 to its middle or neutral position seen in Figure 9, the plate 33 35 however remaining in its rearwardly swung position aforesaid to make the stitch through said rearward hole of the button.

The member 53 is now in the turned position seen in Figure 7 so that, preparatory to making 40 the stitch through the button's forward hole 11¹, 12¹ (Figure 2) or 11² (Figure 1), the rising end portion 56 of lever 35 engages the other side 54 of member 53 and the parts are operated similarly to, but reversely from, the manner above 45 described in order to swing plate 33 forwardly, etc.

In Figure 16 is shown an embroidery stitching 68 which may be made on a fabric, and in Figure 17 is shown a stitching 69 for a button hole 70 50 which may be made by the oscillating needle 10 of my device.

The invention being intended to be pointed out in the claims, is not to be limited to or by details of construction of any particular embodiment 55 thereof illustrated by the drawings or hereinbefore described.

I claim:

1. A sewing machine device of the character described comprising: mechanism for oscillating 60 the machine's needle sidewise including a needle carrier carried by the machine's vertically reciprocating needle bar and having a horizontal movement relatively thereto, an arm having a turning movement on the carrier parallel therewith from a spring-pressed neutral position to opposite positions for moving the carrier with it, and a trigger pivotally mounted in a position fixed relatively to the needle bar's movement and spring-pressed from neutral position and 65 having upwardly diverging opposite sides with one of which sides said arm engages in one upward movement of the needle bar for first turning the arm from its neutral position and thereby moving the carrier to one oscillated position and 70 75

then turning the trigger past its neutral position and with the other one of said sides said arm engages in the next upward movement of the needle bar for first turning the arm oppositely from its neutral position and thereby moving the carrier to opposite oscillated position and then oppositely turning the trigger.

5. A sewing machine device of the character described comprising: mechanism for oscillating the machine's needle sidewise including a needle carrier carried by the machine's vertically reciprocating needle bar and having a horizontal movement relatively thereto, an arm having a turning movement on the carrier parallel thereto with from a neutral position to opposite positions for moving the carrier with it, and a trigger pivotally mounted in a position fixed relatively to the needle bar's movement and having upwardly diverging opposite sides with one of which sides 10 said arm engages in one upward movement of the needle bar for first turning the arm from its neutral position and thereby moving the carrier to one oscillated position and then turning the trigger past its neutral position and with the other one of said sides said arm engages in the next upward movement of the needle bar for first turning the arm oppositely from its neutral position and thereby moving the carrier to opposite oscillated position and then oppositely turning the trigger.

3. A sewing machine device of the character described comprising: mechanism for oscillating the machine's needle sidewise including a needle carrier carried by the machine's vertically reciprocating needle bar and having a horizontal movement relatively thereto and carrying a horizontally extending arm, and a trigger pivotally mounted in a position fixed relatively to the needle bar's movement and spring-pressed from neutral position and having upwardly diverging opposite sides with one of which sides said arm engages in one upward movement of the needle

bar for first moving the carrier to one oscillated position and then turning the trigger past its neutral position and with the other one of said sides said arm engages in the next upward movement of the needle bar for first moving the carrier to opposite oscillated position and then oppositely turning the trigger.

4. A sewing machine device of the character described comprising: mechanism for oscillating the machine's needle sidewise including a needle carrier carried by the machine's vertically reciprocating needle bar and having a horizontal movement relatively thereto and carrying a horizontally extending arm, and a trigger pivotally mounted in a position fixed relatively to the needle bar's movement and having relatively inclined opposite sides with one of which sides said arm engages in one movement of the needle bar for moving the carrier to one oscillated position and turning the trigger past its neutral position and with the other one of said sides said arm engages in a subsequent movement of the needle bar in the same direction for moving the carrier to opposite oscillated position and oppositely turning the trigger.

5. A sewing machine device of the character described comprising: mechanism for oscillating the machine's needle sidewise including a needle carrier carried by the machine's vertically reciprocating needle bar and having a horizontal movement relatively thereto and carrying a horizontally extending arm, and a trigger pivotally mounted in a position fixed relatively to the needle bar's movement and having relatively inclined opposite sides with one of which sides said arm engages in one movement of the needle bar for moving the carrier to one oscillated position and with the other one of said sides said arm engages in a subsequent movement of the needle bar in the same direction for moving the carrier to opposite oscillated position.

DEWEY L. CONNER.
